Primary Examiner — Prabhakar Deshmukh*(74) Attorney, Agent, or Firm* — Kagan Binder, PLLC**(57) CLAIM**

The ornamental design for shaped spindle of a door handle for operating a door lock box, as shown and described.

DESCRIPTION

FIG. 1 is a perspective view of a shaped spindle of a door handle for operating a door lock box showing my new design;

FIG. 2 is an opposite perspective view of the spindle of FIG. 1;

FIG. 3 is a top plan view thereof;

FIG. 4 is a left side elevation view thereof;

FIG. 5 is a right side elevation view thereof; and,

FIG. 6 is a front elevation view thereof.

The broken lines illustrate the unclaimed portions of the design and form no part of a claimed design. The spindle and lock box as collectively illustrated within FIG. 1, are shown separately for clarity of illustration.
